FENCE POST DRIVER AND PULLER

Merrill C. Nichols, Fontanelle, Iowa

Application October 3, 1951, Serial No. 249,435

4 Claims. (Cl. 254—29)

1

My invention relates to improvements in fence post drivers and pullers.

Driving fence posts on the farm has always been hard work. On the relatively large farms that are now common, the fence rows constitute many, many feet in length. When driving these posts with hand equipment, such as sledge hammers or heavy mallets, there is a tendency to peen and even split the ends of the posts as they are being driven. Furthermore, when the posts are set manually, it is necessary either to have two people to carry on the job or to set the posts in pre-dug holes. In the event the posts are driven there is a considerable period of time during the driving of each post when there is little or nothing for the second man to do. During these times of relatively high labor costs, one cannot easily afford to pay for non-working help. The other horn of the dilemma is not any more attractive. If post holes must be dug, each post will require considerable time and effort to place it securely in the ground. In addition to the difficulties already pointed out, it is customary to place fence posts in the ground so that their longitudinal axis is perpendicular to a level plane. Only by so inserting the posts can the most effective fence be constructed. In addition to the utility of so setting the posts, there is the psychological benefit of a better looking fence. When driving posts manually it is only the skilled worker who can sink a post so it is perpendicular to a level plane. Recently, furthermore, the various agricultural schools in the United States have been recommending that fence rows be moved periodically.

If the farmer is to follow this recommendation from the experts, it is necessary that he pull, as well as drive, considerable number of fence posts. With the need for pulling fence posts comes an entirely different problem which is that of exerting a relatively strong upward pull or of digging around each post so as to loosen it. Here again manual methods result in the expending of enormous physical energy and a great waste of time. It is obvious also that the difficulties of driving fence posts are multiplied by the need for moving fence rows. I have developed an attachment for prime movers which will utilize the mechanical strength of the machine to do all of this work.

In view of the foregoing difficulties, therefore, it is the principal object of my invention to provide a single device that can be used to either pull or drive a fence post.

More particularly I embody the use of vertically movable grapping means movable in two directions respectively by hydraulic power.

A further object of my invention is to provide

2

a fence post puller and driver of the above class that is adapted for use on a tractor or the like having a fluid pressure means associated therewith.

Still another object of this invention is to provide a tractor mounted fence post driver and puller that will exert a force perpendicular to the horizontal even though the tractor be on uneven ground at the post site.

It is a still further object of my invention to provide a fence post driver and puller that is capable of setting and pulling fence posts of varying lengths.

A still further object of my invention is to provide a device having the above described characteristics that requires no tools for attaching to or detaching from a fence post.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is an enlarged perspective view of my new fence post driver and puller ready for attachment to a tractor or the like.

Fig. 2 is a side elevational view of my invention showing it mounted on a tractor and engaging a metal fence post preparatory to driving it into the ground.

Fig. 3 is an enlarged top plan view of this device as shown in Fig. 2.

Fig. 4 is a side elevational view of this invention showing it engaging a metal post preparatory to pulling it from the ground.

Fig. 5 is a view similar to that of Fig. 5, but showing this device adapted for use on wooden posts, and

Fig. 6 is a cross-sectional view taken on the line 6—6 of Fig. 5.

Referring to the drawings I show the rear portion of a tractor chassis 10 (Fig. 2) and one of the rear tractor wheels 12 to more fully illustrate the manner in which my invention is used. A pair of fluid pressure hose lines 14 are connected to a source of fluid pressure (not shown) associated with the tractor engine and a suitable manually operated control valve 16 is provided for the hose lines 14. An elongated rigid metal inverted L-shaped supporting bar bracket 18 is secured at its bottom in any suitable manner to the rear chassis portion 10 so that the upper inverted L-portion 20 extends perpendicularly therefrom and to the rear. The free end of the

portion 20 is provided with a transverse opening 22 (Fig. 4).

A double acting hydraulic cylinder 24 with the plunger rod 26 on one end has a boss member 28 extending longitudinally from the other end. This cylinder 24 is mounted to the bracket portion 20 by extending the boss 28 upwardly through the opening 22 and securing it therein by any suitable means such as the nut 30 so that the cylinder is in a vertical plane as shown. The opening 22 is larger than the boss 28 to provide a loose fit and the nut 30 is arranged only as a stop means to keep the boss 28 from slipping from the opening 22 and is not tightened against the bracket portion 20. This allows the cylinder 24 some freedom in a lateral swinging movement so that it will hang perpendicular to the horizontal, even though the tractor is on uneven ground. The broken lines for the bracket 18 in Fig. 2 illustrate this feature by showing a position of this bracket if the tractor were resting on an upward slope. It will also be understood that the boss 28 should be long enough to allow a vertical movement of the bracket portion 20 between the top of the cylinder 24 and underside of the nut 30 corresponding to the lateral movement of the vertical portion of the bracket 18. Thus, in effect, the cylinder 24 is to a certain extent swingably depending from the bracket support portion 20.

Secured to the bottom of the cylinder 24 and extending rearwardly therefrom at right angles is a brace member 32. On the outer end of this brace 32 is an arcuate or U-shaped fence post guide 34 which may be integral therewith or separately affixed such as by welding or the like. Intermediate the guide bar 34 and cylinder 24 is a vertical collar or rod guide 36 that is integrally formed with the brace 32. To the free end of the plunger 26 I have secured a rigid block 38, and also to this block a rod member 40 is secured at its bottom so as to extend upwardly through the collar member 36 and be slidably therein. Preferably the rod 40 is substantially of the same length as the plunger 26 and when arranged as described, it moves with the plunger. The support for this rod 40 offered by the collar 36 serves to relieve side pressure on the rod 26 and the usual packing through which it travels.

A grappling member 42 is formed by bending a metal bar or angle iron into a C-shape and has a pair of metal strap members 44 secured thereto by welding or the like, so as to extend outwardly from one side in parallel spaced relationship to form a clevis as shown in Fig. 1. The strap members 44 extend respectively at opposite sides of the rod 40 and are vertically pivotally secured at their ends to the block 38 by means of bolts and nut or a pin 46 or the like. The hose lines 44 are secured respectively to the top and bottom of the cylinder 24 in a well known manner for providing two way action against the plunger rod 26.

In operation of this device after the tractor has been located at the post site, the grapple member 42 is engaged with a post 48 or 50 as follows. It can be maneuvered so that the post will pass sidewise through the open side of the C-shaped grapple and for pulling a post this method of engagement must be used if the top of the post is higher than the grapple when the plunger is fully retracted. If the post is not too high, however, the grapple may be dropped over the top by extending the plunger and if this is done, the grapple must of course be held hori-

zontal to keep it from binding until it has reached the desired position. For driving a post for example, where there was no post before, it is only necessary to pass the post through the grapple and position it on the ground. Once the grapple has been arranged on the post movement of the plunger downwardly (Fig. 2) or upwardly (Fig. 4) will cause the grapple to pivot on the pin 46 in the opposite direction respectively and effect a binding action on the post. Obviously the arcuate grappling member must be freely pivotable in at least a substantially vertical plane. Since the post serves to hold the grappling member as well as the grappling member holding the post, however, the movement of the grappling member need not be limited to swinging in a vertical plane. The continued movement of the plunger under hydraulic pressure then will drive or pull the post accordingly, and in this operation the upper portion of the post will lean against and be guided by the guide member 34. It will be understood that the tractor itself acts as the resistance force to the resistance of the ground through which the post moves.

In Fig. 5 I show a wooden post 50 which is distinguishable from the metal post 48 and is of a larger diameter, and for using this device on wooden posts, it is only necessary to construct the grapple hook 42 and post guide 34 of suitable dimensions to be usable thereon in the same manner as described above. In this respect it is observed that no change in the shape of the grappling member is necessary as its arcuate interior allows it to serve with equal efficiency on flange type posts or round ones.

Some changes may be made in the construction and arrangement of my fence post driver and puller without departing from the real spirit and purpose of my invention, and it is my intention to cover by my claims, any modified forms of structure or use of mechanical equivalents which may be reasonably included within their scope.

I claim:

1. In combination with a tractor or the like having a source of hydraulic pressure, a support brace mounted on said tractor, a hydraulic cylinder swingably depending from said support member, a plunger rod in said cylinder extensible and retractable at the bottom thereof, a brace member on said cylinder, a vertical collar integral with said brace member, a block member secured to the outer end of said plunger rod, a rod member secured at one end to said block member and having its other end slidably extending through said collar, a grappling member pivotally secured to said block member, and said cylinder connected to said hydraulic pressure whereby said plunger rod is movable in two vertical directions respectively.

2. In a fence post driver and puller, a support member, a two way hydraulic cylinder swingably depending from said support member and having a movable plunger rod that moves downwardly when being extended and upwardly when being retracted, a brace member on said cylinder, a vertical collar integral with said brace member, a post guide member secured to said collar, a block member secured to the outer end of said plunger rod, a rod member secured at one end to said block member and having its other end slidably extending through said collar, a grappling member pivotally secured to said block member, and said cylinder having means whereby it can be connected to a source of fluid pressure.

3. In combination with a tractor or the like having a source of hydraulic pressure, a support brace mounted on said tractor, a hydraulic cylinder swingably depending from said support member, a plunger rod in said cylinder extensible and retractable at the bottom thereof, a vertical collar secured to said cylinder, a rod member secured at one end to the outer end of said plunger rod and having its other end slidably extending through said collar, a grappling member pivotally secured to said plunger rod, and said cylinder connected to said hydraulic pressure whereby said plunger rod is movable in two vertical directions respectively.

4. In combination with a tractor or the like having a source of hydraulic pressure, a support brace mounted on said tractor, a hydraulic cylinder swingably depending from said support member, a plunger rod in said cylinder extensible and

retractable at the bottom thereof, a vertical collar secured to said cylinder, a block member secured to the outer end of said plunger rod, a rod member secured at one end to said block member and having its other end slidably extending through said collar, a grappling member pivotally secured to said block member, and said cylinder connected to said hydraulic pressure whereby said plunger rod is movable in two vertical directions respectively.
